US00D889531S

(12) **United States Design Patent** (10) **Patent No.:** **US D889,531 S**
Canales et al. (45) **Date of Patent:** **** Jul. 7, 2020**

(54) **SPORT EYEGLASSES WITH TEMPLES AND NOSE PADS**

(71) Applicant: **ROKA Sports, Inc.**, Austin, TX (US)

(72) Inventors: **Robert Allen Canales**, Austin, TX (US); **Kurt Robert Spenser**, Austin, TX (US); **Tobin Rohrbach**, Austin, TX (US); **James Donald Oman**, Austin, TX (US); **David S. Ginther**, Austin, TX (US); **John Brandon Currie**, Austin, TX (US); **Steven Oldham**, Austin, TX (US); **Eric Baptiste**, **Suburu**, Austin, TX (US); **Mark Niiro**, Austin, TX (US); **Jonathan McCann**, Austin, TX (US); **Mark Stephens**, Austin, TX (US)

(73) Assignee: **Roka Sports, Inc.**, Austin, TX (US)

(**) Term: **15 Years**

(21) Appl. No.: **29/658,437**

(22) Filed: **Jul. 31, 2018**

(57) **CLAIM**

The ornamental design for sport eyeglasses with temples and nose pads, as shown and described.

DESCRIPTION

FIG. 1 is a perspective view of sport eyeglasses with temples and nose pads, showing our new design;

FIG. 2 is a top plan view of the sport eyeglasses with temples and nose pads;

FIG. 3 is a front elevation view of the sport eyeglasses with temples and nose pads;

FIG. 4 is a right side elevation view of the sport eyeglasses with temples and nose pads;

FIG. 5 is a left side elevation view of the sport eyeglasses with temples and nose pads;

FIG. 6 is a rear elevation view of the sport eyeglasses with temples and nose pads; and,

FIG. 7 is a bottom plan view of the sport eyeglasses with temples and nose pads.

The broken lines in the drawings represent portions of the sport eyeglasses with temples and nose pads that form no part of the claimed design.

1 Claim, 5 Drawing Sheets
